aware

Application May 31, 1939, Serial No. 276,594

8 Claims. (CL 178—7.5)

This invention relates to television signal-translating systems and more particularly to an arrangement for stabilizing a video-frequency television signal and controlling the contrast ratio of the repeated signal in a single vacuum-tube amplifier circuit. The invention is, therefore, especially directed to the provision of an improved background-illumination insertion and contrast-adjusting system for television receivers.

In accordance with present television practice, a transmitted signal comprises a carrier wave modulated during successive intervals, or trace periods, by video-frequency and unidirectional components representative of light variations in an image being transmitted and of its average background illumination, respectively. Between the trace periods, that is, during retrace intervals, the carrier has a predetermined amplitude level referred to as the blanking level, corresponding to a given shade, usually black, and is modulated during a part of this retrace period by synchronizing components which correspond to initiations of successive lines and fields in the scanning of the image.

At the receiver, a beam is so deflected as to scan and illuminate a target or screen in a series of fields of parallel lines. The synchronizing components of the received signal are separated from the other modulation-signal components and utilized to control the scanning apparatus of the receiver so as to synchronize its operation with that of similar apparatus utilized at the transmitter in developing the signal. The intensity of the beam is controlled by the transmitted light-modulation components, thereby to reconstruct the image.

An important requirement in a properly operating television receiver is accurate stabilization of the modulation signal with respect to a particular signal level, usually the peak level representing the synchronizing-signal components, as the signal is applied to the reproducing device, in order to ensure that the background-illumination component is present in the signal. Stabilization is also necessary for setting of the black level in the signal-reproducing device; that is, for optimum operation, the system must be so controlled that a given signal level or amplitude corresponding to black, or any predetermined shade value, is effectively held fixed with respect to the signal input-brightness characteristic of the signal-reproducing device of the system, in order that signal components representing any other given shade will, at all times,

appear as the same shade in the reproduced image.

Furthermore, the eye of an observer is responsive primarily to the contrast or ratio between 5 illumination values rather than the absolute value of any given shade of illumination of an object. Therefore, it is important to provide an arrangement for adjusting to an optimum value the extreme values of illumination in the reproduced image corresponding to signals representing white and black in the transmitted image; that is, the contrast ratio of the reproduced image should be adjustable at the receiver in accordance with conditions of reception and the type of picture being received.

To these ends, it is attempted in conventional television receiving systems so to control the system that the modulation signal is stabilized with respect to a particular signal level as applied to 10 the signal-reproducing device and to provide also an arrangement for controlling the amplitude range of the signal input to the reproducing device. As a result, the signal level or amplitude corresponding to black or any predetermined shade value is effectively held approximately 15 fixed with respect to a particular point on the signal-input-brightness characteristic of the reproducing device of the system and the gain of amplifier circuits in the system is adjusted in order to control the contrast ratio. Certain arrangements of the prior art have provided a separate tube, usually a diode, for stabilizing the video-frequency modulation signal and have provided gain control in one or more additional amplifier tubes in order to control the contrast ratio. Other arrangements of the prior art have provided stabilization by means of peak rectification 20 in the input circuit of a video-frequency amplifier tube and have provided for contrast-ratio control by means of amplification control of a separate video-frequency amplifier. In prior art arrangements, it has not been possible to provide both of these controls in the same stage of a video-frequency amplifier for the reason that, in 25 the prior art, the arrangement utilized to control the amplification of the video-frequency amplifier to control the contrast ratio of the reproduced signal is also effective to change the signal is stabilized which is, in general, an undesirable characteristic.

It is an object of the present invention, therefore, to provide a television signal-translating system including an improved modulation-signal 30 stabilizing and contrast-ratio control circuit

which is free from one or more of the above-mentioned disadvantages of the arrangements of the prior art.

It is a further object of the invention to provide a television signal-translating system including a stabilization control and contrast-ratio control embodied in a single stage of amplification.

In accordance with the present invention, a television signal-translating system comprises a signal-translating channel adapted to have applied thereto an unstabilized television-modulation signal having trace and retrace intervals and varying during trace intervals in accordance with video-frequency components having a wide range of frequencies and during retrace intervals in accordance with synchronizing-signal components. A video-frequency amplifier stage including a single vacuum-tube having an input circuit is provided in the signal-translating channel, together with means for adjusting the effective transconductance of the vacuum tube to control the gain of the amplifier over the frequency range of the video-frequency components of the signal, thereby to control the contrast ratio of the reproduced picture. Effective transconductance, as utilized in this specification, relates to the change in the output current of the amplifier for a given change in input voltage thereto. Means are also comprised within the above-mentioned amplifier stage substantially unresponsive to the gain control of the stage for stabilizing the translated modulation signal at the input circuit of the amplifier at a predetermined level, usually the peaks of the synchronizing signal components.

In accordance with the preferred embodiment of the invention, the means for adjusting the gain of the amplifier stage comprises means for adjusting degeneration in the stage, while the grid circuit of the tube acts as a peak rectifier stabilizer substantially independent of the circuit for providing a degenerative control, thus to provide stabilization which is substantially unresponsive to the gain control utilized for contrast-ratio control.

For a better understanding of the present invention, together with other and further objects thereof, reference is had to the following description taken in connection with the accompanying drawing, and its scope will be pointed out in the appended claims.

In the accompanying drawing, Fig. 1 is a circuit diagram, partly schematic, of a cathode-ray tube television-receiving system including circuits embodying the present invention, while Figs. 2 and 3 are graphs utilized to explain the operation of the circuit of Fig. 1.

Referring now more particularly to Fig. 1 of the drawing, the system there illustrated comprises a receiver of the superheterodyne type including an antenna system 10, 11 connected to a radio-frequency amplifier 12 to which are connected in cascade, in the order named, an oscillator-modulator 13, an intermediate-frequency amplifier 14, a detector 15, a video-frequency amplifier 16, and a cathode-ray signal-reproducing device 17. The cathode-ray tube 17 comprises the usual envelope 18 containing, in the order named, a cathode 19, a signal input or control grid 21, and other conventional elements (not shown) of a cathode-ray signal-reproducing tube. Line-frequency and field-frequency scanning coils 26 and 27 are disposed about the tube for de-

flecting the beam in two directions normal to each other.

A line-frequency generator 31 and a field-frequency generator 32 are also provided, coupled to the output circuit of detector 15 for synchronization and connected to scanning coils 26 and 27, respectively, of the cathode-ray tube in a conventional manner. Suitable means are included in the circuits of generators 31 and 32 for selecting the synchronizing-signal components from other modulation components and from each other in a conventional manner. The stages or units just described, with the exception of video-frequency amplifier 16, presently to be described, may all be of conventional well-known construction so that detailed illustrations and descriptions thereof are unnecessary herein.

Referring briefly to the general operation of the system described above as a whole, television signals intercepted by the antenna circuit 10, 11 are selected and amplified in the radio-frequency amplifier 12 and supplied to the oscillator-modulator 13, wherein they are converted to intermediate-frequency signals which, in turn, are selectively amplified in the intermediate-frequency amplifier 14 and delivered to the detector 15. The modulation components of the signal are derived by the detector 15 and are supplied to the video-frequency amplifier 16 wherein they are amplified and from which they are supplied to the control grid 21 of the cathode-ray tube 17 in a conventional manner. The detected signal components are also supplied to the generators 31 and 32 to synchronize the operation thereof. Under proper operating conditions of the tube 17, an electron beam is emitted from the cathode 19 and accelerated and focused on its fluorescent screen and its intensity is controlled by the control grid 21 in accordance with the video-frequency voltages and control voltages impressed thereon.

Saw-tooth current waves are generated in line-frequency and field-frequency generators 31 and 32, which are controlled by the detected synchronizing-signal components, and these waves are applied to the scanning elements 26, 27 of the cathode-ray tube 17 to produce electric scanning fields, thereby to deflect the ray in two directions normal to each other so as to trace a rectilinear scanning pattern on the screen of the tube and reconstruct the transmitted picture.

Referring now more particularly to the portion of the system embodying the present invention, the video-frequency stage 16, included in the signal-translating channel of the receiver, comprises a single vacuum tube 35 having input electrodes coupled to detector 15 and output electrodes coupled to the cathode-control grid circuit of signal-reproducing tube 17 through a load circuit including a resistor 36 through which a unidirectional operating potential is applied to the anode of tube 35 from a suitable source indicated as +B. A potential divider including a series-connected resistor 37 and resistor 38 having an adjustable tap is coupled across the source of anode supply of tube 35, by-pass condenser 39 being connected between the tap on resistor 38 and ground and the tap on resistor 38 being connected directly to the cathode of tube 17 to provide a bias therefor. An unby-passed cathode resistor 40 is connected in the common signal-input and signal-output circuits of tube 35 and has an adjustable tap thereon for providing adjustable degeneration to control the gain of the stage of the video-frequency amplifier including

tube 35, thereby to control the contrast ratio of the reproduced picture. The input circuit of tube 35 is connected and proportioned to operate as a peak detector in order to stabilize the translated signals and, for this purpose, the grid of tube 35 is coupled to detector 15 by way of a condenser 44 and is provided with a load circuit including a grid-leak resistor 41 coupled between the control electrode and cathode of tube 35.

In considering the operation of the portion of the system which has just been described, it will be assumed that the wave form of the signal developed at the output circuit of detector 15 varies somewhat in accordance with curve 42 shown adjacent the detector output circuit but stabilized with respect to the peaks of the synchronizing pulses and that this voltage is impressed upon the input circuit of the stage of amplification including tube 35 through coupling condenser 44. This wave form illustrated corresponds, in general, to the video-frequency wave form of conventional television practice with the direct-current component removed. Due to the action of the coupling condenser 44, the unidirectional component of the signal supplied by detector 23 is lost, if it is present in the output signal derived from detector 15, and the signal tends to center itself about the zero axis and to appear, therefore, as illustrated by curve 42. In order for a signal of the wave form of that of curve 42 to be useful at the reproducing device 17, it must be stabilized, as explained above. The circuit constants of the input circuit of tube 35 are so proportioned that the grid condenser 44 and grid leak 41 cause the tube 35 to operate as a peak grid rectifier, automatically varying the bias of the control grid of tube 35 which, in the absence of a signal, is provided with zero bias. The signal is thus stabilized at the output circuit of tube 35 as shown by curve 43; that is, the synchronizing peaks of modulation are established at a substantially fixed level as they appear in the output circuit of the tube, and the unidirectional background-illumination component is thereby reinserted in the signal as applied to the cathode-ray reproducing device 17.

Furthermore, as explained above, since the eye of an observer is responsive primarily to the contrast or ratio between the illumination values rather than the absolute value of any given shade of illumination of an object, it is desirable to provide an arrangement for adjusting the contrast ratio of the signal reproduced by tube 17 in accordance with the type of television picture being viewed and other operating conditions. The contrast ratio of the reproduced signal depends upon the ratio of the illumination corresponding to white to that of black. This is more clearly illustrated by the curves of Fig. 2 in which the signal-input-brightness characteristic of cathode-ray tube 17 is represented by curve A. For a signal input in accordance with curve B and of a given amplitude, the effective voltage swing of the input signal, as applied to the input circuit of tube 16, is represented by values s_1 and s_2 , corresponding to a contrast ratio of w_1/b . If the amplitude of the signal input is increased, its form remaining unchanged, as shown in curve C of Fig. 2, the swing of the input signal of tube 17 then varies between the limits of s_1 and s_2 and the corresponding contrast ratio is w_2/b . It is, therefore, seen that an adjustment of the gain of tube 35 is an effective way of varying the contrast ratio of the reproduced signal. Re-

sistor 40, as connected in the circuit of Fig. 1, is an unby-passed cathode resistor and is, therefore, effective to provide degeneration in the stage of amplification. Thus, the contrast of the reproduced signal may be adjusted by adjusting the tap on resistor 40 to control the amount of degeneration in the stage of amplification including tube 35. Inasmuch as the load circuit comprising resistor 41 of the input or detector portion of tube 35 is separate from the degenerative circuit including resistor 40, the peak detector effectively provided is unaffected by changes of value of resistor 40 and the signal output of detector 15, as applied through coupling condenser 44 and represented by curve 42, is stabilized, as illustrated in curve 43, on the peaks of the synchronizing pulses regardless of variations in the adjustment of the tap on resistor 40. Stated in another way, since the grid leak is returned from the control grid to the cathode of tube 35, the direct potential lead in the control grid cathode path will always be established at approximately zero volts for the most positive portion of the input signal independent of the setting of cathode resistor 40.

In summary, therefore, the television signal-translating stage of the invention comprises a signal-translating channel, adapted to have applied thereto from detector 15 through condenser 44, an unstabilized television modulation signal having trace and retrace intervals and varying during trace intervals in accordance with video-frequency components having a wide range of frequencies and during retrace intervals in accordance with synchronizing-signal components. The video-frequency stage 16 in this channel includes a single vacuum-tube amplifier 35 having an input circuit and including the adjustable unby-passed degenerative resistor 40, common to the input and output circuits of tube 35, which provides means for adjusting the effective transconductance of the vacuum tube 35 to control the gain of the amplifier over the frequency range of the translated components. The stage also includes peak-rectifier means, including the cathode and control electrode of tube 35 as well as a load resistor 41 connected directly between the cathode and the control electrode, which is substantially unresponsive to the gain control for stabilizing the translated modulation signal at a predetermined level thereof, specifically, for stabilizing the translated modulation signal at the level of the peaks of the synchronizing components.

While applicant does not intend to be limited to any given circuit values for the embodiment of the invention illustrated, there follow values of circuit elements for a particular embodiment which have been found to be particularly advantageous.

60	Condenser 44	microfarad	0.1
	Resistor 41	megohms	2
	Resistor 40	ohms	0-1,000
	Tube 35		Type 1852
65	Impedance of the load circuit of tube 35	ohms	5,000

An embodiment of the invention utilizing the particular circuit values given above has been found to provide relative gain-frequency characteristics substantially as shown in Fig. 3 for different adjustments of the tap on resistor 40, effectively to provide a cathode-biasing resistor in accordance with values given on the respective curves.

While there has been described what is at

present considered to be the preferred embodiment of this invention, it will be obvious to those skilled in the art that various changes and modifications may be made therein without departing from the invention, and it is, therefore, aimed in the appended claims to cover all such changes and modifications as fall within the true spirit and scope of the invention.

What is claimed is:

1. A television signal-translating system comprising, a signal-translating channel adapted to have applied thereto an unstabilized television modulation signal having trace and retrace intervals and varying during trace intervals in accordance with video-frequency components having a wide range of frequencies and during retrace intervals in accordance with synchronizing-signal components, a video-frequency stage in said channel including a single vacuum-tube amplifier having an input circuit, means for adjusting the effective transconductance of said vacuum tube to control the gain of said amplifier over the frequency range of said components, and means comprised within said stage and substantially unresponsive to said gain control for stabilizing the translated modulation signal at the input circuit of said amplifier at a predetermined level thereof.

2. A television signal-translating system comprising, a signal-translating channel adapted to have applied thereto an unstabilized television modulation signal having trace and retrace intervals and varying during trace intervals in accordance with video-frequency components having a wide range of frequencies and during retrace intervals in accordance with synchronizing-signal components, a video-frequency stage in said channel including a single vacuum-tube amplifier having an input circuit, means for adjusting the effective transconductance of said vacuum tube to control the gain of said amplifier over the frequency range of said components, and means comprised within said stage and substantially unresponsive to said gain control for stabilizing the translated modulation signal at the input circuit of said amplifier at the level of the peaks of said synchronizing components.

3. A television signal-translating system comprising, a signal-translating channel adapted to have applied thereto an unstabilized television modulation signal having trace and retrace intervals and varying during trace intervals in accordance with video-frequency components having a wide range of frequencies and during retrace intervals in accordance with synchronizing-signal components, a video-frequency stage in said channel including a single degenerative vacuum-tube amplifier having an input circuit, means for adjusting the degeneration of said vacuum-tube amplifier to control the gain of said amplifier over the frequency range of said components, and means comprised within said stage and substantially unresponsive to said gain control for stabilizing the translated modulation signal at the input circuit of said amplifier at a predetermined level thereof.

4. A television signal-translating system comprising, a signal-translating channel adapted to have applied thereto an unstabilized television modulation signal having trace and retrace intervals and varying during trace intervals in accordance with video-frequency components having a wide range of frequencies and during retrace intervals in accordance with synchronizing-signal components, a video-frequency stage in said channel including a single vacuum-tube

amplifier having input and output circuits, an adjustable unby-passed resistor common to said input and output circuits for controlling the gain of said amplifier over the frequency range of said components, and means comprised within said stage and substantially unresponsive to said gain control for stabilizing the translated modulation signal at the input circuit of said amplifier at a predetermined level thereof.

5. A television signal-translating system comprising, a signal-translating channel adapted to have applied thereto an unstabilized television modulation signal having trace and retrace intervals and varying during trace intervals in accordance with video-frequency components having a wide range of frequencies and during retrace intervals in accordance with synchronizing-signal components, an amplifier in said channel comprising a vacuum tube having a cathode, a control electrode, and an anode, means for adjusting the effective transconductance between said control electrode and said anode to control the gain of said amplifier over the frequency range of said components, and means including said control electrode and said cathode connected to operate as a peak rectifier and substantially unresponsive to said gain control for stabilizing the translated modulation signal at the input circuit of said vacuum tube at a predetermined level thereof.

6. A television signal-translating system comprising, a signal-translating channel adapted to have applied thereto an unstabilized television modulation signal having trace and retrace intervals and varying during trace intervals in accordance with video-frequency components having a wide range of frequency and during retrace intervals in accordance with synchronizing-signal components, an amplifier in said channel comprising a vacuum tube having a cathode, a control electrode, and an anode, means for adjusting the effective transconductance between said control electrode and said anode to control the gain of said amplifier over the frequency range of said components, and peak-rectifier means including said control electrode, said cathode, and a load resistor connected directly between said control electrode and said cathode and substantially unresponsive to said gain control for stabilizing the translated modulation signal at the input circuit of said vacuum tube at a predetermined level thereof.

7. A television signal-translating system comprising, a signal-translating channel adapted to have applied thereto an unstabilized television modulation signal having trace and retrace intervals and varying during trace intervals in accordance with video-frequency components having a wide range of frequencies and during retrace intervals in accordance with synchronizing-signal components, a vacuum-tube amplifier in said channel including a cathode, a control electrode, and an anode, means including an unby-passed cathode resistor for said vacuum tube to control the gain of said amplifier over the frequency range of said components, and peak-rectifier means including said cathode, said control electrode, and a resistor connected directly between said cathode and said control electrode and substantially unresponsive to said gain control for stabilizing the translated modulation signal at the input circuit of said amplifier at a predetermined level thereof.

8. A television signal receiver comprising a

video-frequency translating channel adapted to have applied thereto an unstabilized television modulation signal having trace and retrace intervals and varying during trace intervals in accordance with video-frequency components having a wide range of frequencies and during retrace intervals in accordance with synchronizing-signal components, a video-frequency stage in said channel including a single vacuum tube amplifier having an input circuit, a contrast-ratio

control means for said receiver including means for adjusting the effective transconductance of said vacuum tube to control the gain of said amplifier over the frequency range of said components, and means comprised within said stages and substantially unresponsive to said contrast-ratio control for stabilizing the translated modulation signal at the input circuit of said vacuum tube at a predetermined level thereof.

ARTHUR V. LOUGHREN.
